COUNTER TOP MOUNTING FOR BUILT-IN TOASTER

Ulysses S. Grant V, Rte. 1, Box 659, Escondido, Calif.

Filed Dec. 9, 1963, Ser. No. 77,710

Term of patent 3½ years

(Cl. D81—10)

Fig. 1

Fig. 2

Fig. 3

Fig. 4

FIGURE 1 is a perspective view of a counter top mounting for a built-in toaster, showing my new design;

FIGURE 2 is a similar perspective view thereof, but with the cover raised;

FIGURE 3 is an end elevational view thereof, as taken from either end of FIGURE 1; and

FIGURE 4 is a sectional view taken on line 4-4 of FIGURE 3.

The toaster shown in broken lines in FIGURES 3 and 4 is included for illustrative purposes only.

I claim:

The ornamental design for a counter top mounting for built-in toaster, as shown and described.
